UNITED STATES PATENT OFFICE.

GOTTLIEB H. SIMON, OF KIEL, WISCONSIN.

MILK-VAT.

No. 866,394.

Specification of Letters Patent.

Patented Sept. 17, 1907.

Application filed March 21, 1907. Serial No. 363,643.

To all whom it may concern;

Be it known that I, GOTTLIEB H. SIMON, a citizen of the United States, residing at Kiel, county of Manitowoc and State of Wisconsin, have invented new and 5 useful Improvements in Milk-Vats, of which the following is a specification.

My invention relates to improvements in sheet metal milk vats and it pertains to that class which is used for heating milk in the process of making cheese.

10 The construction of my invention is explained by reference to the accompanying drawings in which,

Figure 1 is a bottom view. Fig. 2 is a vertical transverse section drawn on line $x-x$ of Fig. 1. Fig. 3 is a detail showing an enlarged view of the seams and 15 strengthening flanges together with the reinforcing plates which are used to strengthen the bottom of the vat at the junction of the longitudinal transverse seams formed in the bottom of the vat. Figs. 4 and 5 are details.

20 Like parts are identified by the same reference characters throughout the several views.

The vat comprises the side pieces 1, end pieces 2 and the bottom 3, and such parts are constructed of a plurality of sections of sheet metal 4. The number of 25 such pieces or sections vary of course according to the size of the vat or sections of sheet metal. The several sections of sheet metal have their contiguous edges bent outwardly at right angles to their central portions and secured together in such a manner as to form seams and 30 strengthening flanges. It will be understood that these vats are subject to great pressure and strain amounting to several tons. For this reason the seams of the several sections of the vat must be of great strength. That the seams may have the required strength the opposing 35 edges of the sections both at the bottom and sides are made of double thickness by folding the edges back upon themselves as indicated in Figs. 2 and 3 at substantially right angles to their central portions and such parts being bent as shown between points A B and B C.

40 As additional means of adding strength to the structure, I preferably insert an additional sheet metal plate or disk E between the opposing surface of the seams when the upper edge of the disk is bent over upon the bottom 3 of the vat, while the lower portion of the disk is 45 bent upwardly in a U shape in the opposite direction beneath the opposing section of the bottom as shown in Figs. 2 and 3, when the seams and joints thus formed are securely soldered together.

It will be understood that the upper edge of the disk 50 E is bent at right angles parallel to the bottom of the

vat above the transverse seams H as indicated in dotted lines in Fig. 1, and as clearly shown in Figs. 2 and 3, while the lower edge of said disk E is bent in the opposite direction around the longitudinal seam I of the vat.

Heretofore it has been common to form the transverse 55 seams upon one side of the longitudinal center of the vat in line with those upon the opposite side of the vat. By the construction shown, however, the transverse seams H upon one side of the longitudinal center terminate midway of the opposing section of the metal upon 60 the opposite side of such longitudinal center, whereby a strain that would otherwise have a tendency to separate the sections at the junction of said seams when all of said seams unite at a common center is divided and more uniformly distributed and the sections are less 65 liable to be torn asunder by the pressure against it.

In practical use two vats of similar construction are 70 preferably used together as shown in Fig. 2 in which case the exterior vat is made larger and supported from a rectangular frame 5 by the supporting leg 6, when the smaller vat is supported from and within the larger vat. The milk to be heated is placed in the interior vat and is usually heated by hot water located in the exterior vat, the seams of the respective vats being formed in like manner.

To give additional strength to the seams and strengthening flanges H at the corners H' of the vat, I preferably provide such flanges with an inclosing cap 10, which is formed of a piece of flexible sheet metal and bent to conform to the said vertical and side portions 75 of the flange as shown in Figs. 4 and 5 when such caps are secured in place by solder in the usual manner.

Having thus described my invention what I claim as new and desire to secure by Letters Patent is,

1. In a milk vat of the described class the combination 85 of a plurality of sections of sheet metal having their contiguous edges respectively bent outwardly at right angles to their central portions and folded back upon themselves so as to perform the two-fold function of seams and strengthening flanges and means of securing said folded edges together, substantially as set forth.

2. In a milk vat of the described class the combination 95 of a plurality of sections of sheet metal having their contiguous edges respectively bent outwardly at right angles to their central portions and folded back upon themselves so as to perform the two-fold function of seams and strengthening flanges and means of securing said folded edges together, the transverse seams between the sections upon one side of the longitudinal center of the vat being united with the longitudinal seam between the transverse 100 seams upon the opposite side of such longitudinal center, substantially as set forth.

3. In a milk vat of the described class the combination of a plurality of sections of sheet metal having their con-

tiguous edges respectively bent outwardly at right angles to their central portions and folded back upon themselves so as to perform the two-fold function of seams and strengthening flanges, a reinforcing disk located at the junction of said longitudinal and transverse seams, the upper edge of said reinforcing disk being bent at right angles parallel to the bottom of the vat above the transverse seam, while the lower edge of said reinforcing disk is folded in the opposite direction beneath and around

said longitudinal seam, and means for securing said seams and reinforcing disk together, all substantially as and for the purpose specified.

In testimony whereof I affix my signature in the presence of two witnesses.

GOTTLIEB H. SIMON.
